UNITED STATES PATENT OFFICE.

FRANCIS H. RICHARDS, OF HARTFORD, CONNECTICUT, ASSIGNOR TO THE STANLEY RULE & LEVEL COMPANY, OF NEW BRITAIN, CONNECTICUT, A CORPORATION OF CONNECTICUT.

MITER-BOX.

SPECIFICATION forming part of Letters Patent No. 766,795, dated August 2, 1904.

Application filed October 2, 1903. Serial No. 175,426. (No model.)

To all whom it may concern:

Be it known that I, FRANCIS H. RICHARDS, a citizen of the United States, residing at Hartford, in the county of Hartford and State of Connecticut, have invented certain new and useful Improvements in Miter-Boxes, of which the following is a specification.

This invention relates to and has for an object to provide an improved miter-box.

10 In wood-sawing machines, such as miter-boxes, it is found practical to support the work upon a table and position it thereon by a back plate or flange and to securely guide a saw relative to such table and back plate, the 15 guiding means being shiftable from place to place thereon and adapted to be securely locked in the adjusted position. To give ample means for so adjusting and locking the saw-guiding device, the present invention is 20 a material improvement over the art as it now exists and which will be more clearly understood by referring to the drawings accompanying and forming part of this specification, wherein—

25 Figure 1 shows a top view of a miter-box constructed to embody the present improvement and wherein the board of the table is broken away to show the parts below. Fig. 2 is a front view thereof with the guide-rods 30 and guide broken. Fig. 3 is a central cross-section showing one of the guides broken and the beam-arm also broken. Fig. 4 is a top view, enlarged, of one end of the beam-arm. Fig. 5 is a longitudinal section thereof, showing the actuator in side view. Fig. 6 is a section on line 6-6 of Fig. 4 looking in the direction of the arrow. Fig. 7 is a section on the line 7-7 of Fig. 4 looking in the direction of the arrow. Fig. 8 is a section on the line 40 8-8 of Fig. 7 looking downward or in the direction of the arrow. Fig. 9 shows the same parts shown in Fig. 6, but in a different position; and Fig. 10 is a similar view of Fig. 7, showing the same amount of shaft rotation as 45 does Fig. 9.

The main frame of the box is shown as comprising a bottom plate 20, supported by suitable feet 21, secured thereto by screws 22, and

a back plate 23, which may be rigid with the bottom plate. Upon the bottom plate is shown 50 a table or board 24, upon which the work will rest and be positioned by the back plate, which has a saw-opening 25. The saw will be carried by a frame which may include a beam-arm and appropriate saw-guides, which frame may 55 have for a base the structure shown herein and in the present instance by a swiveled beam-arm 30, pivoted by a screw 31 to a hub 32, located below the saw passage-way. The frame is shown as having a protruding portion 33, in the present instance arc-shaped, having its center at the line of the axis of the beam-arm. Such segment is shown as provided at its under side with a series of index holes or notches 34, which in the present instance are located at various degrees from the normal central line or the angle of ninety degrees from the back plate and which will permit the saw to cut when located by such index at various angles. The present arrangement 60 and designation of the angles show them designated from such central line, so that the hole marked "60°" will be sixty degrees from such line or thirty degrees from the work-positioning face of the back plate. The beam-arm 65 may be provided with an index-pin 35, which may be called an "indexer" and may be a bolt of any convenient form and which will mate with said notches and be located thereby at the desired position. The beam-arm 70 may also be provided at each end with a saw-guide (designated in a general way by 36) and comprising a pair of guide-rods 37, supporting guide-cylinders 38, which have a saw passage-way 39 to guide and control the saw. 75 The segment is shown as having a rearwardly-projecting flange 40, upon which is a guiding and clamping face 41, in the present instance projecting upwardly, and an opposite or downwardly-projecting face 42 to coöperate with 80 a guiding-face 43 upon the beam-arm and through which guiding-faces, respectively, the index-holes open and the index-pin will operate. A suitable clamp may be carried by the beam-arm to engage such clamping-face 85 41 and draw the guiding-faces together, which

clamp in the present instance is shown as comprising a lever 45, which has a clamping-head 46 to run upon the clamping-face 41 and is pivoted at 47 to the beam-arm and having an actuating end 48 projecting therebeyond. The clamp in the present organization is controlled by a rotary or oscillatory member, which member may be a shaft-actuator or an actuator in the form of a shaft, in the present instance comprising a rock-shaft 49, mounted in suitable bearings 50 of the beam-arm and having a winged head 51 for its actuation. It will be observed that the working face of the clamping-rail is at all times protected from injury and from the accumulation of dirt and that the clamping member is also protected and is so positioned relatively to the other parts of the apparatus that it occupies a position out of the way of the work and of the other parts. Its longer end projecting inwardly places it in a position where it may be constructed of any desired length without cramping or inconvenience to the structure. A spiral spring 52 surrounds a portion of such rock-shaft and engages a collar 53 fast upon it, the other end of the spring engaging one of the bearings. The end of the rock-shaft is provided with a cam 54 to engage the end 48 of the lever, which cam is seen in cross-section in Figs. 6 and 9. When the rock-shaft is held at idle position responsive to its spring, it will hold the clamp securely in its clamping position and bind the clamp-faces of the frame and beam-arm together, whereby the beam-arm will be held from oscillation upon its axis. The rock-shaft also has a cam 55, as seen more clearly in Figs. 7 and 10, which cam in the present instance is made by cutting or channeling the rock-shaft, whereby it will engage a face on the index-pin (illustrated as a lug 56) and withdraw the same. There is as the parts are arranged in this illustration a certain amount of lost movement between the cam and the lug, whereby the clamp may be partially released before the withdrawal of the index-pin. The pin is shown as carrying an engaging face, which may be a lug 57, running in a channel 58 in the beam-arm, in which channel will be seated a spiral spring 59 to throw the pin into its working position. The pin is also provided with a face 60 concentric with the face 61 of the shaft, whereby after the withdrawal of the pin further rotation of the rock-shaft will hold it in its withdrawn position and will also hold the clamp in its relaxed position. As at present constructed the cam 54 is supported by one of the bearings 50, which will be located immediately adjacent thereto, and the cam for the index-pin will be supported in a similar manner, the index-pin channel or socket being located in the upper portion of one of such bearings.

When it has been determined at what angle the saw is to make its cut, the rock-shaft will be rocked so as to release the clamp and with-

draw the index-pin from the hole it then occupies, and the beam-arm may then be swung upon its pivot. When the workman sees that the same is approaching the desired angle, he may release the rock-shaft slightly to the influence of its spring and permit the index-pin to come within the influence of its spring, but holding the clamp from its full clamping action, whereby slight friction will be given to the beam-arm, and the pin will be free to enter the hole, after which of course the workman may release his hand from the rock-shaft and the spring will permit the clamp to become active. The clamp and the pin in this present instance perform their respective and combined work on substantially the same general principles as in the structure made the subject of my application for United States Letters Patent executed by me on the 2d day of October, 1903, and bearing Serial No. 175,421; but in the present instance the parts are illustrated as controlled by a rotary instead of a reciprocatory actuator, as illustrated in the other application. In the former instance a lever-actuator was employed, whereas in the present instance I employ a shaft-actuator, which in the form herein illustrated is common to both the bolt and the clamp. The actuation of the controlling-rod first slightly releases the clamp, then commences the withdrawal of the bolt or index-pin, during which withdrawal the clamp is further relaxed. The bolt is in its withdrawn position at the time of relaxation of the clamp, and upon the release of the actuator to its spring, but while under the control of the workman, the clamp will become active and slightly bind the parts; but the actuator may be held in such position that the index-pin will respond to its spring and enter a hole, after which the clamp upon being released to the full influence of the spring applied to it or its actuator will become active to its full extent. The index-pin not only serves as an index, but also as a bolt coöperating with the clamp, and such index-pin also acts as a precisionizer, which latter function may be performed when the clamp is held from its clamping action, but the index-pin is free to respond to its spring. The pin will when the clamp is brought to its general position enter one of its holes and by slightly moving such arm precisionize the same. Such precisionizing could not be done if the clamp was held at a full clamping strength sufficient to lock it in position. The pin or bolt and clamp are controlled by the same mechanical member, here shown as a rock-shaft, and by the same movement of such member; but at different degrees of its angular advance various concurrent results will be accomplished. The clamp is permitted or caused to release or modify its grip on the withdrawal of the bolt, and upon the release of the bolt to the influence of its spring the clamp will become stronger in its grip. At

the incipient stage of bolting the grip of the clamp is weak and increases as the bolt enters the bolt-hole—that is, if the beam is brought to substantially the correct position before 5 the return rotation of the rock-shaft.

The apron and truss-frame shown and described in this application are claimed in my copending application, Serial No. 175,425, filed October 2, 1903, and the coöperating 10 index-pin and clamping means herein shown and described are broadly claimed in my copending application, Serial No. 175,421, filed October 2, 1903.

Having thus described my invention, I 15 claim—

1. In a miter-box, the combination with a frame to position the work, of saw-guides; a beam pivoted to the frame and carrying the guides; a series of index-holes on the frame 20 corresponding to the positions at which the beam will in practice generally be halted; an index-pin carried by the beam to enter said holes; a rock-shaft to actuate the pin; and a clamping member under the control of said 25 rock-shaft to lock the beam when positioned by the pin.

2. In a miter-box, the combination with a frame to position the work, of saw-guides; a beam pivoted to the frame and carrying the 30 guides; a series of index-holes on the frame corresponding to the positions at which the beam will in practice generally be halted; an index-pin carried by the beam to enter said 35 holes; a rock-shaft to actuate the pin; means to actuate the rock-shaft; and a clamping member under the control of said rock-shaft to lock the beam when positioned by the pin.

3. In a miter-box, the combination with a frame to position the work, of saw-guides; a 40 beam pivoted to the frame and carrying the guides; a series of index-holes on the frame corresponding to the relative positions at which the beam will in practice generally be halted; an index-pin carried by the beam to enter 45 said holes; a shaft-actuator to actuate the pin; a clamping-rail upon the frame; a clamping-lever pivoted to the beam and having a face to run upon said rail; and a face upon said shaft-actuator to control said lever.

50 4. In a miter-box the combination with a frame, of a saw-carrying beam pivoted to the frame; an index-bolt carried by the beam; a series of index-notches on the frame; a clamping-lever also carried by the beam; and an 55 actuator-shaft carried by the beam and having faces to actuate the bolt and the clamping-levers respectively.

5. In combination with a miter-box, a beam to carry a saw; a clamp to secure the beam; 60 a rock-shaft to control the clamp; bolt-holes on the box; a bolt-socket in the beam; a bolt mounted therein and comprising a pin and a body portion; a spring bearing-face at the end of the body adjacent to the pin; a spring- 65 chamber adjacent to the bolt-socket; a spring

therein to throw the bolt; a bearing-face on the other side of the body at the opposite end thereof; and a cam on the rock-shaft to engage said latter bearing-face and draw the bolt. 70

6. The combination with a miter-box, of a saw-guiding frame carried thereby; index-pin holes on the box; an index-pin carried by the frame to mate with such holes; a clamping-lever carried by the frame; a rock-shaft carried thereby and having a cam-face 75 to control said clamping-lever; a bearing-face on the index-pin; a cam-face on the shaft to engage said bearing-face and draw said pin; and a locking-face on the rock-shaft to hold the pin in its withdrawn position during part 80 of the clamp-releasing rotation of the rock-shaft.

7. In a miter-box, the combination with a frame; a saw-carrying beam pivoted to the 85 frame; a series of index-pin holes on the frame; an index-pin carried by the beam; a clamping-lever also carried by the beam; and a rock-shaft having fixed bearing-faces to 90 actuate the pin and clamping-lever respectively. 90

8. In combination with a miter-box, of a beam to carry a saw; a clamping-block to secure the beam; a rock-shaft; a spiral cam thereon to control the block; bolt-holes on the box; a bolt-socket in the beam; a bolt 95 mounted therein and comprising a pin and a body portion; a spring-receiving lug at the end of the body adjacent to the pin; a spring-chamber adjacent to the bolt-socket; a spring therein to throw the bolt; a lug on the other 100 side of the body at the opposite end thereof; and a cam on the rock-shaft having an idle face to clear the lug to permit idle movement to the cam, an engaging face to engage said lug and draw the bolt; and a concentric face to hold the bolt drawn during the 105 continued action of said spiral cam.

9. In combination with a miter-box, a saw-guiding frame pivoted thereto; bolt-holes on the box; a bolt carried by the frame; means to throw the bolt; a clamping-face on the box; a clamping member carried by the frame; a rock-shaft to withdraw said bolt and relax said clamping device; and means to 110 return said rock-shaft to its normal position whereby the clamping member is rendered positive in its action and the bolt permitted to respond to its individual throwing means. 115

10. In combination with a miter-box, a frame pivoted thereto and organized to guide a saw; a clamping-lever to hold the frame in its adjusted position; a rock-shaft; means to hold the rock-shaft in its normal position; and a cam on the rock-shaft to actuate the clamping-lever and adapted to hold the same 120 at its work when the rock-shaft is in its normal position. 125

11. In combination with a miter-box, a saw-guiding frame shiftable thereon; bolt-holes on the box; a bolt carried by the frame; means 130

to throw the bolt; engaging guiding-faces on the box and frame; a clamping-face on the box adjacent to the guiding-face and toward the opposite direction; a clamping member carried by the frame and running upon the clamping-face; a rock-shaft to withdraw said bolt and relax said clamping member; and means to return said rock-shaft to its normal position.

12. In combination with a miter-box, a frame pivoted thereto and organized to guide a saw; a clamping-lever to hold the frame in its adjusted position; a rock-shaft; means to automatically return the rock-shaft to its normal position and hold the same thereat; and a cam on the rock-shaft to actuate the clamping-lever and adapted to hold the clamp in its gripping position when the rock-shaft is in its normal position.

13. In combination with a miter-box, a beam-arm pivoted thereto and carrying saw-guides; a member to precisionize the position of the beam-arm; a clamping-lever to hold the same at an adjusted position; a rock-shaft; means to automatically return the rock-shaft to its normal position and hold the same thereat; and cams on the rock-shaft to actuate said member and lever and adapted to normally hold the clamp in its gripping position.

14. In combination with a miter-box embodying a table, of a beam-arm to carry a saw-guide and pivoted thereto; a clamping-block to secure the beam-arm relative to the work-table; a rock-shaft to control the block; bolt-holes on the box; a bolt-socket in the beam-arm; a bolt mounted therein and comprising a pin and a body portion; a spring-bearing at the end of the body adjacent to the pin; a spring-chamber adjacent to the bolt-socket; a spring therein to throw the bolt; a face on the body at the opposite end thereof; and a cam on the rock-shaft to engage said face and draw the bolt.

15. The combination with a miter-box, of a saw-guiding frame pivotally supported thereby; index-pin holes on the box; an index-pin carried by the frame to mate with such holes; means to throw the pin; a clamping member carried by the frame; a rock-shaft carried thereby and having a cam-face to control said clamping member; a lug on the index-pin; a cam-face on the shaft to engage said lug and draw said pin; a locking-face on the rock-shaft to hold the pin in its withdrawn position during part of the clamp-releasing rotation of the rock-shaft; and a face to release the pin to the influence of its throwing means during the partial clamping action of said member.

16. In combination with a miter-box embodying a work-table; a beam-arm pivotally carried thereby; a precisionizing-pin carried by the beam-arm; means to throw the pin; a rock-shaft; a cam on the rock-shaft to draw the pin; means to clamp the beam-arm; and means in the control of the rock-shaft to modify the

clamping action during the precisionizing action.

17. In a miter-box the combination with a work-table, of a beam-arm pivoted thereto and adapted to swing thereunder; a guide-face on the lower side of the table; a guide-face upon the upper side of the beam and adapted to engage the guide-face upon the table; an indexer carried by the beam; recesses upon the table for the engagement of the indexer; a clamp carried by the arm and adapted to clamp the guide-faces together; and a rotary actuator common to both the clamp and the indexer to operate the same.

18. In a miter-box, the combination with a frame to position the work, of saw-guides; a beam pivoted to the frame and carrying the guides; a series of index-holes on the frame corresponding to the positions at which the beam will in practice generally be halted; an index-pin carried by the beam to enter said holes; a rock-shaft to actuate the pin; a clamping member under the control of said rock-shaft to lock the beam when positioned by the pin; and means for yieldingly impelling the pin to engage the index-hole when the rock-shaft operates to close the clamp.

19. In a miter-box, the combination with a frame to position the work, of saw-guides; a beam pivoted to the frame and carrying the guides; a series of index-holes on the frame corresponding to the positions at which the beam will in practice generally be halted; an index-pin carried by the beam to enter said holes; a rock-shaft to actuate the pin; means to actuate the rock-shaft; a clamping member under the control of said rock-shaft to lock the beam when positioned by the pin; and means for yieldingly impelling the pin to engage the index-hole when the rock-shaft operates to close the clamp.

20. In a device of the character specified, the combination with a frame; of a saw-carrying beam pivoted to the frame; an index carried by the beam; a series of index-engaging faces upon the frame; a clamping-lever carried by the beam; a rotary actuator carried by the beam and having faces to actuate the index and the clamping-lever respectively; and means independent of the actuator to impel the index to engage the index-faces when the actuator operates to close the clamp.

21. In a miter-box, the combination with a frame; a saw-carrying beam pivoted to the frame; a series of index-pin holes on the frame; an index-pin carried by the beam; a clamping-lever also carried by the beam; a rock-shaft having fixed bearing-faces to actuate the pin and clamping-lever respectively; and means for yieldingly impelling the pin to engage the index-hole when the rock-shaft operates to close the clamp.

22. In combination with a miter-box embodying a work-table; a beam-arm pivotally

carried thereby; a precisionizing-pin carried by the beam-arm; holes for the pin; means to throw the pin; a rock-shaft; a cam on the rock-shaft to draw the pin; means to clamp 5 the beam-arm; means in the control of the rock-shaft to modify the clamping action during the precisionizing action; and means for yieldingly impelling the pin to engage the index-hole when the rock-shaft operates to 10 close the clamp.

23. In a miter-box the combination with a frame to position the work, of saw-guides; a beam pivoted to the frame and carrying the guides; a series of index-recesses on the frame 15 corresponding to positions at which the beam may in practice be halted; an index carried by the beam to engage said recesses; a shaft-actuator to actuate the index, a clamping member under the control of said actuator to 20 lock the beam when positioned by the index; and means for yieldingly impelling the index to engage the recesses when the actuator permits the clamp to close.

24. In a miter-box the combination with a 25 frame, of a saw-carrying beam pivoted to the frame; an index carried by the beam; a series of index-recesses on the frame; a clamping member also carried by the beam; a rotary actuator having fixed bearing-faces to actuate 30 the index and clamping member respectively; and yieldable means to impel the index to engage the recesses when the actuator operates to close the clamp.

25. In a miter-box the combination with a 35 table, of a saw-guiding device shiftable thereon; a clamping-lever carried by said device; an independent positive actuator for said clamping-lever; and a clamping-rail for the engagement of said clamping-lever and carried by 40 the frame and having a working face directly engaged by said clamping-lever directed upwardly and protected by said frame.

26. In a miter-box the combination with a table having a portion to position the work, of a beam-arm pivoted thereto; saw-guides 45 carried by the beam-arm; a lever pivoted to the beam-arm and having a clamping-face; a rail carried by the table and having a clamping-face disposed below the lower side of the table, directed toward the same and covered 50 thereby; and a rotary actuator for said lever.

27. In a miter-box, the combination with a table to carry the work, of saw-guides and a beam-arm to carry the same shiftable about said table; an indexer carried by the beam-arm; an index upon the table; a rail carried by the table and having a clamp-engaging face covered by the said table; a lever carried by the beam-arm having a clamping-face at one end engaging the face of the rail and 60 having its other end project inwardly beneath the table; an actuator adapted to engage such latter end of said lever to actuate the same, and to engage the indexer to actuate the same.

28. The combination with a frame, of saw-guides; a beam-arm carrying the guides and pivoted to the frame; an index on the frame; an indexer on the beam-arm; an actuator to withdraw said indexer from the index; yieldable means to control the actuator; a clamping-face on the frame; and a lever pivoted on the beam-arm and having a face to engage said clamping-face and having a face to be engaged by said actuator to press said clamping-faces together at the release of the indexer and 70 to unclamp the same upon the withdrawal of the indexer.

Signed at Nos. 9 to 15 Murray street, New York, N. Y., this 19th day of September, 1903.

FRANCIS H. RICHARDS.
